UNITED STATES PATENT OFFICE

FREDERICK A. LORENZ, JR., OF CHICAGO, ILLINOIS, ASSIGNOR TO AMERICAN STEEL FOUNDRIES, OF CHICAGO, ILLINOIS, A CORPORATION OF NEW JERSEY

GRATE

Application filed February 11, 1929. Serial No. 338,926.

This invention pertains to grates, and more particularly to the dumping or rocking type of multiple section grates used in locomotive fireboxes or the like.

There are special requirements for grates to be used in locomotive service, which requirements are peculiar to that service alone and which must be constantly borne in mind to produce a successful device, especially as there is an increasing tendency for long runs. One of these requirements is that the grates must be of sufficient width to allow rapid cleaning of the fire. In other words, when the grates are in dumping position, there must be an open space between them large enough to freely pass all clinkers which have been formed. It is not uncommon to replace locomotive grate bars from time to time, the most common cause for replacement being—one: burning of the top surface of the grates, and two: thermal cracks appearing in the top surface of the grates.

Burning or cracking of course necessitates the removal of the entire grate bar so burned or cracked and is due to the fire coming into direct contact with the metal of the bar. The temperature of the fire being far above the fusing temperature of the metal usually used for these grate bars, large holes are produced in the bars which in turn produce holes in the fire which are very detrimental to proper combustion.

Thermal cracks are caused by unequal heating of the grate bar structure. The usual design of structure has a top surface to support the fuel and admit air to the fuel bed, the structure being strengthened on the under side by deep ribs cast integral with the top, and the top surface is often in direct contact with the fire while the strengthening ribs are kept comparatively cool by the rush of air through the grate bar to the fire. This produces a very unequal and bad condition of expansion and contraction in the casting, resulting in thermal cracks in the top surface of the assembly. Once the cracks are started, it is only a question of time as to when they will extend all the way through the casting, and for this reason grates must be inspected very closely at terminals in or-

der that the grate bar may last as long as possible and yet be removed before it breaks, as a breakage on the road would cause "engine failure".

It is therefore desirable to design a grate bar with a separate top which is in contact with and supports the fuel bed, said top being supported on a carrying member, and this carrying member would practically be a permanent part of the locomotive, while the top could be cheaply and quickly removed for replacement.

It is therefore an object of the present invention to provide a grate assembly which is inexpensive to build and maintain, and one which fulfills all of the above enumerated requirements for economical maintenance and successful operation.

Another object is to provide a grate bar assembly which effectively resists distortion, is readily removable and permits rapid cleaning of the fire and changes of the grate bars.

Still another object is to provide a grate assembly which affords substantially no resistance to expansion and contraction, yet at the same time is fixedly supported and effectively resists warping and twisting.

Yet another object is to provide a grate assembly wherein the securing members between parts are reduced to a minimum and wherein the clearances are predetermined and arranged to permit ease of operation, assemblage and replacement.

A still further object is to provide a grate frame or load carrying member which is of ample strength, is air cooled to the greatest possible degree, is designed to hold the top plates firmly in place and yet allows for full expansion and contraction, and finally one which is inexpensive to produce.

A yet further object is to provide a table grate or plate for cooperation with a frame fulfilling the above requirements, said plate being adapted for the uniform admission of air through said plate for proper combustion, the plate being of uniform thickness yet as thin as consistent with strength and rigidity, to the end that the shrinkage stresses are reduced to a minimum. Further, the plate is

designed for free expansion and contraction without affecting the frame, is of such character that the production variations do not materially affect the proper function or firmness of the fastenings of the top to the frame, and the plate is of such character as is easily and inexpensively removed and replaced.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a top plan view of a grate assembly embodying the invention, said view showing the relation of the supporting frame to one of the grate plates;

Figure 2 is a side elevation of the assembly shown in Figure 1;

Figure 3 is an enlarged sectional end elevation of the grate assembly, the same being taken substantially in the plane as indicated by the line 3—3 of Figure 2;

Figure 4 is an enlarged fragmentary side elevation of a portion of the grate plate, showing one of the locking members;

Figure 5 is a top plan view of a modified form of grate assembly embodying the invention, said view showing the relation of the supporting frame to one of the grate plates;

Figure 6 is a side elevation of the assembly shown in Figure 5; and

Figure 7 is an enlarged end sectional elevation of the grate assembly, the same being taken substantially in the plane as indicated by the line 7—7 of Figure 6.

Referring first of all more particularly to the modification illustrated in Figures 1 to 4 inclusive, the grate assembly includes a supporting frame and any number of grate plates (shown 2) which are releasably secured to said frame. The frame 10 consists essentially of a pair of spaced parallel ribs or supporting members 12, shown of substantially truss shape, that is, the greatest depth of the ribs is disposed adjacent the center thereof in order to closely approximate a beam of uniform stress for a uniformly distributed load. Ribs 12 terminate at their ends in integral trunnions 14 of either the socket or horseshoe type, or preferably one of said trunnions 16 is of the socket type while the other of said trunnions 18 is of the horseshoe type. The ribs may also be provided with any number of spaced integral cross members 20 to form a more rigid structure. Each of said ribs 12 is provided with fastening means for the grate plates, which means include pairs of spaced lugs 22, said lugs on each of said ribs being preferably aligned

with corresponding lugs on the other of said ribs.

The grate plates or table grates 24, provided with round or other suitably shaped apertures 26, may be convex in section and may be provided with a marginal rib 28 extending around the plate, said rib and said plate being integral with a longitudinal rib 30 disposed on the concave side of the plate, a cross rib 32 being preferably provided intermediate the length of said plate and integral with the ribs 28 and 30. The plate and rib 32 are provided with spaced downwardly projecting locking lugs 34 and 36 on the opposite sides of the center rib 30, said lugs being adapted to have cooperative engagement with the lugs 22. Lug 34 is preferably substantially inverted T-shaped in elevation, being provided with a shank 38 and a head 40 comprising oppositely extending arms, said arms being adapted to extend beneath and have cooperative engagement with pairs of the spaced lugs 22 provided on the supporting ribs of the frame. Lug 36 is preferably longer than the lug 34 and is provided with an aperture or keyway 42 disposed beneath the lugs 22 in assembly, whereby a cotter pin or key 44 may be inserted in the keyway 42 for locking said plate in its operative position. The other plates may be placed in their respective positions in a similar manner.

It will be seen that with such an assembly the plates are locked in position at a plurality of points on opposite sides of the frame, and supporting engagement between the plates and the frame is maintained at a plurality of points by means of contact of the rib 28 with each of said supporting ribs and with one of the trunnions 14, transverse rib 32 is in contact with each of the supporting ribs, and the longitudinally extending rib 30 may be in supporting engagement with the trunnion and one or more of the transverse tie members 20 of the frame.

Referring now more particularly to the modification illustrated in Figures 5 to 7 inclusive, it will be seen that the assembly includes a supporting frame and any number (shown 2) of grate plates. The supporting frame consists essentially of a pair of spaced longitudinally extending parallel ribs 50 of substantial truss shape, said ribs being formed integrally with suitable trunnions 52 disposed at either end of the frame, and integral cross ties or ribs 54 may be provided at suitable intervals intermediate the ends thereof. The assembly shown is for a pair of grate plates though it is to be understood that an assembly of any number of said plates is contemplated.

In the present instances, it is desirable to lock each of the plates in its operative position with respect to the frame at a plurality of points, and this is done by providing

the frame 50 with inwardly extending spaced lugs 56, said lugs being shown with an aperture 58 for the reception of a locking member provided on the grate plate. While these lugs 56 are shown as closed members provided with apertures, they of course may be made in a manner similar to the lugs 22 already described. The grate plate 60 is preferably of arcuate shape in section, and as shown is provided with a marginal rib 62 extending around the plate and having bearing contact with the frame and with the trunnion. The plate is of course suitably apertured as at 64 and may also be provided with a longitudinally extending rib 66 and a transversely extending rib 68, said ribs 66 and 68 being integral with the other, the marginal flange 62, and with the plate. The under side or convex side of the plates is provided with depending lugs 70, said lugs being adapted to extend through the apertures 58 when the plates are assembled with the frame, and each of said lugs is shown as provided with a keyway 72 adapted for the reception of the key 74 for releasably locking said plates in operative position.

In assembling the frame, each plate is of course merely dropped into position, the lugs 70 extending through the apertures 58, whereupon the keys may be inserted in their respective keyways 72 for maintaining the plates in their operative position.

It will be seen that with the above assembly that a very compact and advantageous structure is provided, and it is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a grate assembly, the combination of a supporting frame, said frame including spaced parallel members and supporting trunnions integral therewith, positioning means on said parallel members including pairs of spaced lugs, grate members supported on said frame, said members each having locking members having cooperative relation with said positioning means, said locking members including headed members engaged under certain of said pairs of lugs and depending members spaced from said headed members and embraced by other pairs of said lugs, and removable keys in said depending members, said keys extending under said lugs for releasably securing said grate members in operative position.

2. In a grate assembly, the combination of a supporting frame, said frame including spaced parallel members and supporting trunnions integral therewith, positioning

means on said parallel members provided on the outside thereof, grate members supported on said frame, said members each having depending locking members having cooperative relation with said positioning means, 70 said locking members including members having inter-engaging relation with said positioning means, and means cooperating with certain of said locking members and said positioning means for releasably securing said 75 grate members in operative position on said frame.

3. In a grate assembly, the combination of a supporting frame, said frame having trunnions integral therewith, positioning means 80 on said frame including pairs of parallel lugs, grate members supported on said frame, said members each having locking members having cooperative relation with said positioning means, said locking member including headed members engaged under certain of said pairs of lugs, depending members spaced from said headed members and embraced by other pairs of said lugs, and removable keys in said depending members, said 85 keys extending under said lugs for releasably securing said grate members in operative position.

4. In a grate assembly, the combination of a supporting frame, said frame including 90 trunnions integral therewith, positioning means on said frame including lugs, grate members supported on said frame, said members having locking members having cooperative relation with said positioning means, 95 said locking members including headed members engaged under certain of said positioning means, and depending members spaced from said headed members and provided with a removable member for engaging under 100 other of said positioning means for releasably securing said grate members in operative position.

Signed at Chicago, Illinois, this 7th day of February, 1929.
